United States Patent Office.

SOLON O. CAMPBELL, OF CENTRETON, MISSOURI.

Letters Patent No. 106,119, dated August 9, 1870.

IMPROVEMENT IN RAILWAY CAR-COUPLING.

The Schedule referred to in these Letters Patent and making part of the same.

To all whom it may concern:

Be it known that I, SOLON O. CAMPBELL, of Centretown, in the county of Cole and State of Missouri, have invented a new and improved Car-Coupling; and I do hereby declare that the following is a full, clear, and exact description thereof, which will enable others skilled in the art to make and use the same, reference being had to the accompanying drawing forming part of this specification, in which—

Figure 1 represents a vertical longitudinal section of my improved car-coupling.

Figure 2 is a vertical transverse section of the same.

Similar letters of reference indicate corresponding parts.

This invention relates to improvement in car-couplings, such as are used without a link, and consists in the construction and arrangement of parts as hereinafter described.

A A, in the drawing, are two coupling-boxes of suitable size and shape, made of cast-iron or other suitable material. The front end of each has two or more forward projecting plates, a a, with rounded front edges, the spaces between every two plates, a, being just large enough to admit one such plate from the opposite box, as shown.

In the front part of each box A is arranged a lever, B, which is fitted through slots of the box and held

down by a projecting pin, b, so that it may swing in the slot.

Its horizontal upper arm contains a sliding coupling-pin, C.

The lever can swing back on its pivot, b, and is thus swung back previous to coupling, while the pins are drawn up as far as possible.

When two boxes, A A, are pushed together to have their plates a interlocked like fingers, the lever B of the higher box will be pushed into a vertical position to make its pin C drop, while the other lever B will be held back by the upper plate a of the higher box, as shown in fig. 1.

The pin C of the higher box will drop through apertures of all the plates A, and will therefore effectually lock the boxes together.

This coupling can be used without a link, but may also be worked together with the same if desired.

Having thus described my invention,

I claim as new, and desire to secure by Letters Patent—

The fingers a of the boxes A, levers B B, and pins C C, when said parts are constructed and relatively arranged as shown and described.
